Primary Examiner — Angela J Lee(74) *Attorney, Agent, or Firm* — Clinton H. Wilkinson;
Charles A. Wilkinson(57) **CLAIM**

The ornamental design for an LED light, as shown and described.

DESCRIPTION

FIG. 1 is a perspective view of an LED light showing our new design;

FIG. 2 is a side view thereof;

FIG. 3 is a bottom view thereof;

FIG. 4 is a top view thereof;

FIG. 5 is a perspective view of another embodiment of our LED light;

FIG. 6 is a side view thereof;

FIG. 7 is a bottom view thereof; and,

FIG. 8 is a top view thereof.

Material in the several views shown in broken lines illustrates variable environmental material associated together with material shown in solid, and forms no part of the claimed design.
